CLAIM

The ornamental design for a microwave oven, as shown and described.

DESCRIPTION

FIG. 1 is a perspective view of a microwave oven in accordance with my new design;

FIG. 2 is a front elevation view thereof;

FIG. 3 is a rear elevation view thereof;

FIG. 4 is a top plan view thereof;

FIG. 5 is a bottom plan view thereof; and,

FIG. 6 is a right side elevational view thereof, the left side elevation being a mirror image thereof.

1 Claim, 6 Drawing Sheets
